UNITED STATES PATENT OFFICE.

H. A. HARVEY, OF NEW YORK, N. Y.

IMPROVED WOOD-SCREW.

Specification forming part of Letters Patent No. 42,475, dated April 26, 1864.

To all whom it may concern:

Be it known that I, HAYWARD A. HARVEY, of the city, county, and State of New York, have invented a new and useful Wood-Screw; and I do hereby declare that the following, taken in connection with the drawings, is a full, clear, and exact description thereof.

In the drawings, Figure 1 is a longitudinal central section through the screw. Fig. 2 is an elevation of the head and part of the shank, and Fig. 3 is a plan of the lower side of the head.

The improved wood-screw herein described has been devised in order to secure a firmer hold in wood, and to prevent in a measure, if not wholly, all the tendency of the screw to jar out of the wood. The improvements are based upon the well known property of expansion of wood after compression.

The screw is to be cut in any usual or proper machine, and the chaser is to be caused to cut deeper than usual at some part of the barrel of the screw between the end of the point and the place where the thread commences, as from A to B. This operation will leave the pitch of the thread the same as in the ordinary screw, but the thread will have greatest projection where the barrel of the screw is smallest in diameter, and also be thinner or come more nearly to an edge at its periphery, as may be clearly seen in the drawings. The barrel of the screw will also be curved longitudinally, so that its diameter near the point is greater than its diameter farther up the shank or barrel, and it is clear that if the barrel were gripped at the small part that it could not be pulled out of the gripper or grasping body if the same were rigid, even if it had no thread. This longitudinal curve in the barrel making the screw bulbous-pointed, is the first feature of the invention, and such bulbous-pointed screws may be made with a thread of varying projection, as shown in the drawings, or with a thread which at all points projects the same distance from the barrel. The former plan is preferred.

The under side of the screw-head represented in the drawings is cut into teeth like ratchet-teeth, so that the screw can be turned easily in one direction when in contact with wood, and cannot be turned except with difficulty in the other. These teeth are so formed with reference to the twist of the screw-thread that their inclined faces compress the wood

and pass over it when the screw is screwed in. When a screw such as is described is forced into wood, the latter will expand after the point has passed and grasp firmly around the small part of the barrel, and when the thread draws the under side of the head down upon the wood the teeth will compress the wood, and when the screw is home the wood expanding will enter into the ratchet-teeth and prevent unscrewing, except by breaking or cutting the wood by the straight sides of the teeth.

I prefer to make these screws with the entering part of the point formed substantially as shown in the drawings, where the convolutions of the thread are represented as extending down the entering part of the point, but stopping short of the extremity thereof.

By this method of construction a center point is formed which forms a guide, causing the screw to enter exactly at the desired location, and also opens the way so that the screw may be screwed in without the necessity of boring a hole, thereby causing the expanding wood to grip firmly around the small part of the barrel. But the extremity of the point may be of any form and the screw still remain bulbous-pointed so long as the barrel is smaller at some part of its length than it is at another part between that small part and the extremity of the point, thereby bringing into action the expanding quality of the wood to secure the screw in place irrespective of the hold of the threads.

I claim as of my own invention—

1. A bulbous-pointed screw, substantially such as is herein described.
2. A bulbous-pointed screw with the thread projecting unequally, so that its periphery will occupy the same position that it would in a screw of the ordinary form of barrel, substantially as described.
3. A bulbous-pointed ratchet-headed screw, constructed and having the mode of operation herein set forth.
4. A bulbous-pointed screw provided with a center point without any thread on the extremity thereof, substantially such as is herein specified.

In testimony whereof I have hereunto subscribed my name:

H. A. HARVEY.

In presence of—

IRA GRIGGS,
W. T. NICHOLSON.
